United States Patent Office.

ROBERT WOLFF, OF NEW YORK, ASSIGNOR TO HIMSELF AND BERNARD SILVERMAN, OF BROOKLYN, NEW YORK.

Letters Patent No. 102,903, dated May 10, 1870.

IMPROVED BRICK-MACHINE.

The Schedule referred to in these Letters Patent and making part of the same.

To all whom it may concern:

Be it known that I, ROBERT WOLFF, of the city and State of New York, have invented an Improvement in Brick-Machines, and the following is declared to be a correct description of the same.

This invention relates to a press in which clay, in a pulverized state, is supplied into molds by a feeding and mixing-screw, and there pressed by followers.

My invention consists in the peculiar construction of mechanism that is combined with the molds and followers, so as to give the necessary pressure upon the bricks, and then deliver the same from the molds by the action of a slide and apron.

In the drawing—

Figure 1 is a vertical longitudinal section;

Figure 2 is a plan of the machine;

Figure 3 is an end view at the delivery-end of the machine, the delivery-apron and frame being removed;

Figure 4 shows the levers and eccentric for moving the mold-cover; and

Figure 5 shows the means for giving pressure upon the followers.

The clay, in a dry state, is introduced into the cylinder A, through the hopper A', and within this cylinder A is a revolving screw-blade, b, the shaft B of which is driven by power applied to the pulleys C C.

This screw b thoroughly mixes the clay, and also forces it along to the delivery-trough D, and I remark that if desired, the clay may be slightly moist, or be moistened by jets of steam led into the cylinder A.

From the shaft B the gears P¹ and P give motion to the shaft K, and from this the cross-shaft I is actuated by the bevel-gears X X.

At the end of the trough D are the brick-molds E, there being any desired number in a range. I have shown three molds, and in the bottom parts of these molds are the followers F, that are upon columns 1 1 1, that are connected with the cross-bearer 2, set at its ends in the levers G G.

The levers G have their fulcrums upon the standards H, and said levers and the followers F are actuated in the manner illustrated in fig. 5.

The yoke M is attached by a bolt, N, to the lever G, and said yoke M is between two disks, L, through which disks pass the arbors of the rollers 5 6 7.

The levers G, being placed one on each side of the bearer 2, and the disks L and yokes M corresponding, I am enabled to obtain from the revolution of the shaft I a very powerful but intermittent action upon the follower, and that with but little friction.

As the disks L (or roller-carriers) revolve, the rollers 5 act upon the yokes and levers, to raise the yoke

M and followers F sufficiently to carry the clay above the lateral opening from D, and then the roller 6 acts against the inner upper part of the yoke M, to cause the followers F to press the brick with great force within the mold, and then the pressure is momentarily relieved as the roller 6 passes its highest point, in order that the cover V of the mold may be drawn back by the means hereafter described, and then the roller 7 acts to raise the parts sufficiently to lift the bricks from the molds, and hold them while the slide-cover V is moved forward again, to press the finished bricks off upon the revolving apron W, to be conveyed away for burning.

The roller 7 moving downward as it revolves, allows the followers to descend and a fresh supply of clay to pass into the mold.

The cover V is fitted in slides above the molds E and trough D, and the eccentrics O, levers P² and P⁴, moving upon the fulcrums R, are made use of to slide said cover at the proper time, the cross-bar S entering at its end-slots in the levers P³.

The cam O may be grooved, so as to move the cover V in both directions, or springs or weights may be used to draw the cover back.

I find that the under portion of the slide V and the followers F and molds E require greasing, to insure freedom of movement. I therefore provide an oil-receptacle, T, with a narrow mouth at the lowest point, through which the oil can percolate, or a strip of lamp-wick or fibrous material can be introduced at this point, and this receptacle T, being upon the forward part of the slide-cover V, lubricates the molds and followers in passing over them.

A rotary brush, to which a rapid movement is given, may be employed to spread the oil. This brush is represented in fig. 1.

If the trough D is removed, a die, such as in Figure 6 or Figure 7, may be employed for making clay pipes or cornices, or other articles.

I claim as my invention—

1. The yoke M and rollers 5 6 7 and revolving shaft I, in combination with the levers G and followers F of the mold for bricks or similar articles, substantially as and for the purposes specified.

2. The slide V, actuated as specified, in combination with the oil-receptacle T and molds E, as and for the purposes specified.

Signed by me this 18th day of February, A. D. 1870.

ROBERT WOLFF.
